UNITED STATES PATENT OFFICE.

CHARLES M. CONKLIN AND EDMUND H. LUNKEN, OF CINCINNATI, OHIO, ASSIGNEES TO THE
LUNKEN STEEL WINDOW CO., OF CINCINNATI, OHIO.

FIREPROOF WINDOW CONSTRUCTION.

No. 903,058.

Specification of Letters Patent.

Patented Nov. 3, 1908.

Application filed November 4, 1907. Serial No. 400,700

To all whom it may concern:

Be it known that we, CHARLES M. CONKLIN and EDMUND H. LUNKEN, citizens of the United States, residing at Cincinnati, Ohio, 5 have invented certain new and useful Improvements in Fireproof Window Construction, of which the following is a specification.

The said invention relates to improvements in fireproof window construction and includes the following objects. First, to provide guide strips upon which the swinging sash is mounted, which may be pressed outward into tight contact with the main frame or casement when the window is closed to make 15 an exceedingly tight weather-proof joint, may be slightly spaced therefrom or the pressure relieved to permit the sash to be readily raised or lowered, or may be withdrawn sufficiently to disengage them entirely from the 20 casement to permit the sash to be swung upon its horizontal pivots for the purposes of cleaning, and ventilation. Second, to provide means by which said guide strips may be simultaneously operated from manipulating mechanism carried by the sash and, to adapt one of the manipulating devices to serve as a sash lock or fastener when the window is closed and the guide strips are 25 pressed into tight contact with the casement. Third, to provide a sash frame made of two parts separably connected together so that the glass may be inserted laterally into the receiving channel of one part and the other applied thereto and quickly and securely 30 locked in position to confine the glass in place, the parts of the sash frame being readily separable to allow the glass to be renewed in case of breakage. Fourth, to provide a sash of separably connected hollow parts forming a frame with a plurality of air spaces and intermediate bracing webs, thereby securing maximum strength and 35 rigidity with a minimum amount and weight of material.

With these and various other minor objects in view, the invention includes the various novel features hereinafter described and particularly set forth in the appended claims.

Referring by reference characters to these drawings Figure 1 represents a front elevation partly broken away, of the lower sash frame to illustrate the application of the invention to the lower sash, the casing and 55 upper sash being omitted in order to show

the parts on a scale sufficiently large to make the drawings clear. Fig. 2 is a cross section on line 2—2 of Fig. 1 together with a portion of the outer frame groove. Fig. 3 is a vertical section on line 3—3 of Fig. 1, looking 60 toward the left and showing the lower portion of the upper sash. Fig. 4 is a vertical section on line 4—4 of Fig. 1 together with a portion of the sill. Fig. 5 is a detailed view of operating connections. Fig. 6 is a view of 65 a modification. Fig. 7 is a cross section on line 7—7 of Fig. 1. Fig. 8 is a detailed view of one of the locking strips. Fig. 9 is a longitudinal section through one of the side bars of the sash frame. Fig. 10 is a sectional detail of a modified form of operating connections.

Referring by reference characters to these drawings, the numeral 1 designates the window frame or casing and 2 the window sash. 75 Both of these parts are constructed of fireproof material, preferably of sheet metal, and the window frame or casement is provided with vertical channels 3 which are preferably formed integral with the plate of 80 the frame 1 and in which the sash guiding strips may slide vertically. The sashes are supported by the sash cords 4 counterbalanced by weights in the usual manner, but as they form no part of the present invention, 85 the weights and sash cord guides are not shown herein. The sash cords are connected to eye pieces 5 in which are journaled the hinge pintles 6, upon which the sash frame 90 hinges.

The sash frame, the particular construction of which will be hereinafter described in detail, is provided in its side edges with channels which receive the guide strips 7. These may be plain channel strips and their edges 95 are inclined inwardly as shown at 7* to coact with correspondingly inclined portions 3* at the edges of the channel portion 3. The rods 8 at the top and bottom of the sash are connected with these strips at their outer 100 ends and extend inward through the top and bottom rails of the sash frame preferably to the center thereof, where they are connected to suitable manipulating devices, by the operation of which the strips may be forced outward to cause their inclined outer edges 7* to bear with a wedging action against the inclined portion 3*, thus forming a perfectly 105 tight weather-proof joint when the sash is in its closed position. Such a connection 110

would exert too much friction to enable the sash to be raised and lowered easily, and consequently the manipulating devices are so arranged that by a determined amount of movement the guide strips 7 may be drawn inwardly within their recesses sufficiently to avoid friction and yet maintain their guiding action, thus permitting the sash to be raised and lowered in the ordinary manner. When, however, the sash is to be swung horizontally upon its pivots 6, further movement of the manipulating devices will draw further upon the rods and move the guide strips 7 inwardly sufficiently far to cause their inclined edges to completely clear the inner faces of the window frame or casement, thus enabling the sash to be readily swung to any desired position.

The preferred construction of sash frame is shown in detail in the sectional views and comprises two hollow sheet metal parts, as 9 and 10, see Figs. 2 and 9. Each of these is preferably formed of a single piece of sheet metal folded upon itself in the shape shown, the two pieces being brought together, with their faces 9^a and 10^a in contact. These faces have portions alternately struck up and depressed with openings in each at the points of junction of the depressed portions with the raised portions, and the raised portions of one bar 9 for example, are arranged in alignment with the depressed portions of the other bar 10. Thus when the two parts or bars are placed with their faces in contact, a locking bar 11 shown in detail in Fig. 8, may be slid longitudinally into the space formed by the overlapping struck up portions and thus securely lock the two portions or bars of the frame together. The bars are provided with projecting or flanged portions 9^b and 10^b, respectively, the latter being offset to provide a space for the reception of the edge of the glass.

It will be understood that the side and cross bars are mitered and welded together at the corners, and where the sash includes a muntin, this also is welded to the cross bars. This provides two integral rigid frames, a front one and a back one, which, when locked together by the locking bars as above described, make an exceedingly strong and durable sash, but one in which the glass may be readily replaced when desired.

The space formed between the flanges 9^b and 10^b is of greater thickness than the glass for the reception of packing or filling material, 11', and 12 and it will be readily seen that the glass is easily and quickly applied by inserting it and the packing strips in place against the flanges 10^b before the removable frame is applied and locked in position.

The filling material 11' which lies against one face and the edge of the glass may be putty, cement, or any suitable material but we prefer to make the layer 12 of a channel

shape or folded strip of spring brass, this strip being located on the side of the glass towards the removable frame part. The folded over edges 9^c and 10^c form the side bearing for the guide strips and from the manner in which these are folded it will be seen that extra thickness of material is provided at this point, thereby not only securing additional strength, but avoiding the necessity of riveting the parts. In the space formed between the inner and outer walls of the side bar 10 is located a block 13 to which the pivot pintle 6 is connected, this passing through an opening in the guide strip 7.

Where the window is provided with a muntin the two frame parts or bars 9^a and 10^a (Fig. 7) are made of substantially similar shape, the one having a central projecting portion 10^c to properly space the flanges to form the glass receiving channels, and provide the overlapping portions for the reception of the locking bar.

The folded edges 9^c and 10^c are made to conform so far as exterior finish is concerned, to the edges of the opposite flanges and for this purpose the outer layer of metal is brought down to and folded around the edge of the inner layer, which latter is bent slightly outward and into the shape shown.

Another advantage in the special construction of sash frame above described, is that it provides a hollow sash frame with a plurality of air chambers and with internal bracing webs or members as the inner walls, which serve as the means for connecting the two parts, serve also as bracing or strengthening webs, thus permitting us to secure maximum strength with the minimum thickness or weight of material. The meeting rails are constructed in substantially the same manner, being only modified to provide the necessary different shape or configuration of the exposed parts. In these no edge channel is necessary and consequently the folded over portions 9^d and 10^d are brought into juxtaposition to provide a flush and substantially continuous surface as shown in Fig. 3. A metal packing strip 14 is secured to each meeting rail preferably by having its curved edge bent around the portion 9^d and held by the clamping strip 14^a. The clamping strip for the lower meeting rail of the upper sash is substantially the same shape as that of the upper rail of the lower sash except that it has an inwardly projecting guard portion extending into the space between the two sashes.

The bottom cross bar or member of the lower sash is modified to adapt it to make a tight joint with the window sill, which is shown at 15. This latter, which is also preferably of sheet metal is provided with a central flange or rib 16 which enters a space or channel 17 between the respective parts of the bottom bar of the sash. The folded over

edges 10' support and hold in position a spring brass packing strip 18 which coacts with the rib or flange 16 to make a tight and weather-proof joint. This construction of 5 the lower sash bar, in conjunction with the particular shape of the window sill, enables us to secure ventilation without the entrance of rain, snow and direct drafts, as by raising the window only a slight distance a circuitous 10 air passage is formed. The inner wall 16^a serves to deflect the incoming air upwardly and in conjunction with the rib or flange 16 effectually prevents entrance of rain or snow. It may be noted that in all of the bars 15 constituting the frame there is a slight space between the ends of overlapping portions as clearly shown in Fig. 9. This allows the members to accommodate themselves to any slight irregularities in manufacture, and provides for any relative movement due to 20 expansion and contraction.

The manipulating device for operating the rods 8 at the top of the lower sash is preferably constructed so as to perform the double 25 function of operating the rods 8 and serving as a sash lock. To secure this we provide a thumb lever 19 carried by a pivot pin 20 journaled in a block or plate 20^a secured in the upper bar. The thumb lever has a projecting 30 arm 21 designed to engage a recess in a keeper 22, secured by means, such as a screw 23, to the bottom rail of the upper sash. The inner ends of the rods 8 are attached by means of suitable eccentric connections to the 35 pin 20 within the hollow portion of the cross bar. These connections are such that when the arm 21 is in locking engagement with the keeper 22 the rods will be pressed outwardly and the guide bars forced into weather-tight 40 engagement with the window casement. When, however, the arm 21 has been moved sufficiently to disengage it from the keeper so that the sash is free to be raised or lowered, the bars 7 will have been withdrawn by the 45 rods only to such a degree that while friction is avoided, they still serve as guides for the sash in its vertical movement. When, however, the sash is to be swung upon its horizontal pivots, the arm 21 is moved still further and the guide bars withdrawn to a still greater degree into the channels in the side 50 bars of the sash frame. The manipulating device for the rods in the bottom rail of the sash, frame operates in substantially the 55 same manner, but is located upon the front face of the sash frame and comprises but a single arm 21^a carried by the pivot pin 20^a which extends through the front wall of the bar and to which on the inside the lower rods 60 8 are eccentrically connected.

Instead of having an independent operating or manipulating device for each set of rods we may connect them by a rod running through one of the vertical members of the 65 sash, and have the manipulating handle lo-

cated on either cross bar desired. Such a construction is shown in Fig. 10 in which the pivot pin 20 is continued in the form of a rod 20^b through the central muntin and into the lower bar, where it is caused to operate the 70 rods by suitable eccentric connections similar to those of the upper bar. This may of course be arranged either with or without the locking feature.

It will be understood that substantially 75 the same guide bars, rods and manipulating devices would be applied to the upper sash. They would be practically a duplication, however, of the corresponding parts of the lower sash, the only modifications necessary 80 being those due to the reverse position of the upper sash with relation to the lower, and hence we have not deemed it necessary to show the upper sash in the drawings.

In some cases we might find it desirable to 85 dispense with the positive control of the rods so far as their outward movements is concerned and simply have them pressed out by yielding pressure and capable of being drawn in when the sash is to be swung on its horizontal pivots. Such a construction is shown in Fig. 6 where the rods are provided with thumb pieces 8^a projecting through an elongated opening in the frame bar and are normally forced apart by an interposed spring 95 8^b though capable of being drawn together to draw the guide bars out of the guides.

Having thus described our invention what we claim is:—

1. The combination with a window frame 100 having sash guides, of a sash having channeled side edges, laterally movable guide bars seated in said channels, rods connected to said bars and extending to the center of the top and bottom rails, and manipulating 105 devices carried by said rails for imparting longitudinal movement to the rods, substantially as described.

2. The combination with a window frame 110 having sash guides, of a sash having channeled side edges and hollow cross bars, laterally movable guide bars slidably seated in said channels, rods connected to said guide bars and extending through said hollow cross bars and means for imparting longitudinal movement to said rods, substantially as described.

3. The combination with a window frame 115 having sash guides, of a sash having channeled side edges and hollow cross bars, laterally movable guide bars slidably seated in 120 said channels, rods connected to said guide bars and extending through said hollow cross bars to the center of the sash, and manipulating devices upon the outer faces of 125 said cross bars for imparting longitudinal movement to the rods, substantially as described.

4. The combination with a window frame 130 having sash guides, of a sash frame having hollow cross and vertical members, laterally

- movable guide bars carried at the sides of the frame, means extending through the horizontal members for imparting lateral movement to said guides, and a connection through a vertical member whereby said means in the horizontal members are operated simultaneously.
5. The combination with a window frame having sash guides, of a sash frame having hollow cross bars and a hollow muntin, laterally movable guide bars at the sides of said frame, rods connected to said bars and extending within the horizontal members, a rotatable rod located within the muntin, eccentric connections between said rotatable rod and the rods in the horizontal bars, and means for rotating said rotatable rod.
6. The combination with a window frame having sash guides and a sash having laterally movable guide bars, of rods for moving said bars and a manipulating device for operating said rods, said device having means for locking the sash against movement when the guide bars are pressed against the guides, substantially as described.
7. The combination with a window frame having sash guides and upper and lower sash having channeled sides and laterally movable guide bars, of rods connected to said bars and extending inward to the center of the top of the lower sash, a device carried by said top bar for reciprocating said rods, a keeper on the bottom rail of the upper sash, and a locking member carried by said device for engaging said keeper, substantially as described.
8. In fire-proof window construction, a sash comprising two frame members, each consisting of hollow sheet metal bars with their inner faces in contact and having glass retaining flanges, said inner faces having respectively overlapping portions, and movable locking means for engaging said overlapping portions, substantially as described.
- 45 9. In fire-proof window construction, a sash having a frame bar, comprising two closed hollow sheet metal members having contacting walls and glass retaining flanges, means for securing said members together, said contacting walls forming a central bracing web, substantially as described.
10. In fire-proof window construction, a sash having a frame bar comprising two hollow sheet metal sections detachably connected together, each of said bars comprising a single piece of sheet metal folded upon itself with the folded edges forming a glass retaining flange, the edges of the sheet being brought together and bent into locking engagement with each other, substantially as described.
- 55 11. In fire-proof window construction, a sash comprising two frame members having flanges for engaging opposite sides of the edges of the glass, and overlapping parts, said parts having spaces between abutting ends, and removable locking means engaging said overlapping parts.
12. In fire proof window construction a muntin comprising two sheet metal members with parallel flanges extending from opposite edges, one of said members having an inwardly extending portion with parts overlapping parts of the other portion, and a key 70 75 slide longitudinally within the muntin for securing said overlapping parts together, substantially as described.
13. In fire-proof window construction, a muntin comprising two hollow sheet metal members with parallel flanges extending from opposite edges, each of said members comprising a single piece of sheet metal bent into hollow form with interlocking edges, one of said members having an inwardly extending portion detachably connected to the inner face of the other.
14. In fire-proof window construction, a sill having a rib or flange and a channel provided with flaring walls, and a sash having a channel to receive said rib, said flaring walls 90 providing a circuitous passage when the sash is slightly raised.
15. In fire-proof window construction, a sash comprising two frame members having flanges for engaging opposite sides of the edges of the glass, and overlapping parts, and locking means movable longitudinally of the frame bars for engaging said overlapping parts.
16. In fire proof window construction a sash composed of two hollow frame members each having side, top and bottom bars, thereby forming interior longitudinally disposed webs dividing the interior into a plurality of air chambers.
- 100 105 17. In fire-proof window construction, a sash comprising two frame members, having means for holding the glass, and means for holding said frame members together while permitting longitudinal movement of the bars of one frame with relation to the corresponding bars of the other frame.
18. In fire-proof window construction, the combination with a window frame having guide ways, of a sash having laterally movable guide bars, for co-operating with the guide ways, rods connected to the guide bars and extending into the top and bottom rails of the sash, said rods adapted to operate the guide bars, substantially as described.
- 115 19. The combination with a window frame having vertical channels, of a sash having hollow cross and channeled side members, guide bars seated in the channels of the side members and engaging the channels in the window frame, hinge pintles carried by the sash and projecting through the guide bars, sash cords connected to said pintles, and rods

in the cross members for imparting lateral movement to the guide bars, substantially as described.

20. The combination with a window frame having sash guides, of a sash having channeled side edges and hollow cross bars, laterally movable guide bars seated in said channels, rods connected to said guide bars and extending through said hollow cross bars, 5 and manipulating devices upon the outer faces of said cross bars for imparting longitudinal movement to the rods, substantially as described.

21. In fire-proof window construction, a sash comprising two frame members having flanges for engaging opposite sides of the edges of the glass, and abutting parts, and locking means movable longitudinally of the frame bars for engaging said abutting parts. 10

22. In fire proof window construction a sash comprising two frame members each having side, top and bottom bars and having means for engaging opposite sides of the edges of the glass, and locking means movable longitudinally of the frame bars for interlocking said frame members substantially as described. 20 25
